UNITED STATES PATENT OFFICE.

HENRY M. PETERS, OF CHICAGO, ILLINOIS, ASSIGNOR TO FARIES MANUFACTURING COMPANY, OF DECATUR, ILLINOIS.

DESIGN FOR A PORTABLE READING LAMP.

Application filed July 9, 1928. Serial No. 27,424. Term of patent 3½ years.

To all whom it may concern:

Be it known that I, HENRY M. PETERS, a citizen of the United States, residing at Chicago, in the county of Cook and State of Illinois, have invented a new, original, and ornamental Design for Portable Reading Lamps, of which the following is a specification, reference being had to the accompanying drawing, forming a part thereof.

Figure 1 is a front elevation, Figure 2 is a side elevation and Fig. 3 is an enlarged detail plan view of the base member forming a part of the design shown in Figs. 1 and 2.

I claim:

The ornamental design for a portable reading lamp as shown.

HENRY M. PETERS.
